UNITED STATES PATENT OFFICE.

MORRIS SCHLEPP, OF NEW YORK, N. Y.

DESIGN FOR A CHANDELIER PLATE.

Application filed November 28, 1921. Serial No. 518,457. Term of patent 7 years.

To all whom it may concern:

Be it known that I, MORRIS SCHLEPP, a citizen of Poland, and a resident of the city of New York, borough of Manhattan, in the county and State of New York, have invented a new, original, and ornamental Design for Chandelier Plates, of which the following is a specification, reference being had to the accompanying drawing, forming part thereof.

In the drawing:

Figure 1 is a bottom plan view of a chandelier plate embodying my new and original design; and

Figure 2 is a view in side elevation of Figure 1.

I claim:

The ornamental design for a chandelier plate, as shown.

MORRIS SCHLEPP.
